DESIGN FOR A COMBINED EXTINGUISHER
AND ASH TRAY

Jack C. Lockwood, Los Angeles, Calif.

Application March 18, 1946, Serial No. 127,613

Term of patent 14 years

(Cl. D85—2)

To all whom it may concern:

Be it known that I, Jack C. Lockwood, a citizen of the United States of America, residing at Los Angeles, in the county of Los Angeles and State of California, have invented a new, original, and ornamental Design for a Combined Extinguisher and Ash Tray, of which the following is a specification, reference being had to the accompanying drawing, forming part thereof.

Figure 1 is a perspective view of a combined extinguisher and ash tray, showing my new design; Figure 2 is a plan view of the combined extinguisher and ash tray; and Figure 3 is a vertical longitudinal sectional view of same taken on the line 3—3 of Figure 2 and looking in the direction of the arrows.

I claim:

The ornamental design for a combined extinguisher and ash tray, as shown.

JACK C. LOCKWOOD.
